Fig. 2

UNITED STATES PATENT OFFICE

RAYMOND L. PLUMLEY, OF BROOKLYN, NEW YORK, ASSIGNOR TO FREDERICK OSANN COMPANY, OF NEW YORK, N. Y., A CORPORATION OF NEW YORK

SEWING MACHINE LIGHT ARRANGEMENT

Application filed July 28, 1928. Serial No. 295,972.

The present invention relates to electric light attachments for sewing machines and has for its object the provision of a lighting fixture unusually simple in construction, effective in operation and inexpensive to manufacture. My invention is particularly adapted for use with high speed sewing machines of the portable type and when so used has certain special advantages hereinafter stated.

10 The various features of novelty which characterize my invention are pointed out with particularity in the claims annexed to and forming a part of this specification. For a better understanding of the invention, however, and the advantages possessed by it, reference should be had to the accompanying drawing and descriptive matter in which I have illustrated and described a preferred embodiment of the invention.

20 Of the drawing:—

Fig. 1 is a rear elevation of my invention; and

Fig. 2 is an end elevation with portions of the light broken away.

25 In the preferred form of my invention shown in the drawing, the sewing machine comprises a base member A upon which is detachably secured the frame casting of the machine. The latter comprises a bed B, a standard C rising from one end of the bed portion and a horizontal arm D supported by the standard C and terminating at its free end in the head E. The top surface of the bed B serves as the cloth surface or work support of the machine. The usual hook actuating mechanism is contained within the bed B and driven from a hook shaft F through a pulley F'. The arm D and head E contain the actuating mechanism for reciprocating a presser bar G and a needle bar H, into the lower end of which a needle H' is inserted. The various operating mechanisms are preferably driven by an electric motor J contained within the bed B and connected to the pulley F' by a belt F''. The motor projects through an aperture in the top surface of the bed B. The sewing machine illustrated is a portable high speed machine such as is described and claimed in the pending

application of R. K. Hohmann, Serial No. 242,368, filed December 24, 1927.

The electric light fixture of my invention is particularly advantageous in machines of this type, and in carrying out my invention I provide a bracket M consisting of a flat plate M' secured to the standard C on the side opposite the operator and at a point thereon adjacent the junction with the arm D by threaded bolts M''. The plate has an upper U-shaped portion M''' inclined away from the standard C and plate M' and arranged to receive a central portion of an incandescent lamp socket. The plate M' is also provided with an integral laterally projecting arm M⁴ having its outer end formed with a clip M⁵ for purposes hereinafter described. A screw threaded bolt N is mounted in an opening in the free end of the U-shaped bracket portion M''' with its threaded portion N' arranged in a threaded opening in the other leg adjacent the standard C. The bolt head is provided with a kerf N² into which a screwdriver or other tool may be inserted for adjusting the bolt N to loosen or tighten the bracket portion M''' about the lamp.

The electric lamp of my invention is mounted in the bracket heretofore described at the rear of the standard C and arranged in such a manner that the longitudinal axis of the lamp passes through the lower part of the needle H' when the latter is in its raised position and intersects the portion of the bed B serving as the work support of the machine.

The electric lamp consists of a substantially cylindrical lamp socket O and a bell-shaped reflector P, each of which is provided with tapered end portions O' and P', respectively, adjacent to and connected to each other. A lamp bulb Q is mounted in the tapered portion of the socket O with its outer end positioned in the reflector. The tapered portion of the reflector is provided with a series of openings R spaced about its circumference and providing ventilation for the lamp bulb Q. As shown in Fig. 1, the lamp is held in an inclined position with respect to the standard C by inserting the reduced portion of the socket O into the U-shaped bracket

portion M^3 as shown in Fig. 2. The electric lamp is held in the bracket by the bolt N securing the legs of the U -shaped portion together. A cord S containing a pair of electric conductors is inserted in the upper end of the socket O and held adjacent the standard C by the clip M^5 . As shown in Fig. 1, the lamp is held in such a position and the reflector and bulb so proportioned and arranged that the light rays are focussed on the needle eye and work where illumination is most necessary.

My invention has other advantages than those heretofore stated. The operator being seated at the side of the machine opposite the lamp will not be subjected to any glare from the light due to the arrangement of the reflector P . Any light rays passing out of the lamp ventilating openings R will be prevented from reaching the operator by the standard C .

The described arrangement of the lamp is particularly advantageous on sewing machines required to be frequently shifted by the user as it leaves the major portion of the horizontal arm free to be grasped by the user in moving the machine. The capacity for such manual operations is particularly important in machines usually requiring manual shifting from an inoperative position to another position in which they are capable of operation, such as, for example, in a light weight portable machine to permit the removal of the same from or restoration to a carrying case or its transporting where desired, and also with a sewing machine of the drop head type in raising the same to or lowering it from its operative position. The lamp being entirely within the reflector P prevents any contact by the hand or arm of the lifter with the bulb Q . The location of the bracket and lamp on the standard C , rather than on the reduced portion of the arm D or head E , also reduces the vibration of the lamp and materially increases the life of the bulb used therein. Both the bracket and lamp are very simple in construction and may be manufactured at a relatively low cost. The lamp socket and reflector are preferably spun together during the assembly of the parts. The fixture may be installed with slight modification of the existing sewing machine to which it is applied. The arrangement of the conductor cord in the bracket clip prevents the possibility of the cord contacting with or becoming entangled in any of the moving parts of the machine.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims

and that in some cases certain features of my invention may be used to advantage without a corresponding use of other features.

Having now described my invention what I claim as new and desire to secure by Letters Patent, is:

1. In a sewing machine having a frame comprising a vertical standard and a horizontal arm projecting therefrom and terminating in a head portion, the combination therewith of a bracket plate secured to said frame adjacent the junction of said standard and arm on the side opposite the operator and having an integral U -shaped projecting portion, an electric lamp mounted in said U -shaped bracket portion and arranged in an inclined position for illuminating the needle and work, and means connected to the free end of said U -shaped portion for securing said lamp in position. 75

2. In a sewing machine having a frame comprising a vertical standard and a horizontal arm projecting therefrom and terminating in a head portion, the combination therewith of a bracket comprising a plate secured to said frame adjacent the junction of said standard and arm on the side opposite the operator and having an integral U -shaped projecting portion inclined relative to said plate, an electric lamp mounted in said U -shaped portion and arranged in an inclined position for illuminating the needle and work, and means extending between the legs of said U -shaped portion for securing said lamp in position. 100

3. In a portable sewing machine having a base plate, a hollow bed secured to said plate, a vertical standard rising from one end of said bed, a horizontal arm connected to said standard, and a head connected to the opposite end of said arm, the improvement which consists of a bracket plate detachably connected to an intermediate portion of said standard on the side opposite the operator, a U -shaped bracket portion connected to and inclined relative to said plate, a lateral arm connected to said bracket plate and having a clip thereon, an electric lamp having a socket and a reflector mounted in said U -shaped bracket portion, an incandescent bulb in said socket, and electric conductors connected to said bulb and arranged to be held in said clip. 110

4. In an electrically driven portable sewing machine having a base plate, a hollow bed secured to said plate, a vertical standard rising from one end of said bed, a horizontal arm connected to said standard, and a head connected to the opposite end of said arm, the improvement which consists of a metallic bracket plate detachably connected to an intermediate portion of said standard on the side opposite to the operator, a U -shaped bracket portion integrally connected to the upper end of said plate and inclined 120

with respect thereto, a lateral arm integrally connected to said bracket plate and having a clip formed thereon, an electric lamp having a socket and a reflector connected to said socket mounted in an inclined position in said U-shaped bracket portion, an incandescent bulb in said socket, and electric conductors connected to said bulb and arranged to be held in said clip.

5. In a sewing machine having a frame comprising a vertical standard and a horizontal arm projecting therefrom and terminating in a head portion, the combination therewith of a bracket having a plate portion secured to said frame adjacent the junction of said standard and arm and a U-shaped projecting portion inclined relative to said plate portion, and an electric lamp having an intermediate reduced portion mounted in said bracket with its intermediate reduced portion within said U-shaped bracket portion, and means securing said lamp therein in an inclined position.

Signed at Brooklyn in the county of Kings
25 and State of New York, this twenty-sixth
day of July A. D. 1928.

RAYMOND L. PLUMLEY.
